BOTTLEHOLDER

Peter Haywa, Minneapolis, Minn.

Application November 9, 1946, Serial No. 708,985

4 Claims. (Cl. 294—87.2)

1

My invention relates to bottle holders and has for an object to provide a bottle holder by means of which bottles may be readily picked up and carried about and readily released from the holder when desired.

An object of the invention resides in providing a holder in which the bottles are firmly held in position so that the same may be inserted as a group into a case or other carrier for the bottles.

A still further object of the invention resides in providing a holder in which the likelihood of injury to the bottles is greatly reduced.

A feature of the invention resides in constructing the holder with a frame formed with spaced upper and lower plates, said plates having rows of holes therein overlying one another and adapted to form pairs of registering holes through which the necks of the bottles may be inserted.

Another object of the invention resides in mounting in said holes, nipples for the reception of said bottles, said nipples being constructed of a relatively soft, flexible material such as rubber or the like.

An object of the invention resides in constructing the nipples with flanges adapted to overlie the outer surfaces of the plates of said frame and holding the nipples attached to the frame.

A feature of the invention resides in forming the nipples flared at their lower ends to facilitate insertion of the necks of the bottles into said nipples.

An object of the invention resides in providing a gang clamp slidable within the space between said frame plates and adapted to simultaneously engage all of the nipples to urge the same against the bottles and hold the bottles mounted in the holder.

Another object of the invention resides in attaching to the upper plate, a bail and in pivoting thereto a lever having an arm adapted to engage the gang clamp and to shift the same along said frame.

An object of the invention resides in constructing the bail with a handle and in constructing the lever with an arm extending generally in the same direction as said handle and in close proximity thereto whereby the gang clamp may be operated upon manipulation of the lever and handle and the lever held in position while the holder is being carried about.

Another object of the invention resides in constructing the gang clamp from a rod and in making the same serpentine in form with spaced

2

transverse grip members adapted to engage the nipples of the holder.

A still further object of the invention resides in providing stops having portions overlying certain of the holes in said plates to limit the downward movement of the holder on the bottles.

Other objects of the invention reside in the novel combination and arrangement of parts and in the details of construction hereinafter illustrated and/or described.

In the drawings:

Fig. 1 is a perspective view of a bottle holder illustrating an embodiment of my invention.

Fig. 2 is a plan view of the structure shown in Fig. 1 with portions of the same broken away to illustrate the gang clamp of the invention.

Fig. 3 is an elevational sectional view taken on line 3—3 of Fig. 1.

Fig. 4 is a fragmentary view similar to Fig. 2 and illustrating the parts in altered position.

In the use of bottle holders for transporting a plurality of bottles, breakage and injury to the bottles frequently results due to the contact of the bottles with the metal of the holder and due to the insecure manner in which the bottles are supported in the holder. Such devices frequently require separate operations for locking the bottles within the holder, thus making such devices slow and inconvenient to use. The present invention provides a construction whereby the bottles may be quickly and easily mounted in the holder and when so positioned are firmly and securely attached thereto in a manner to prevent injury to the bottles.

My improved bottle holder comprises a frame A which consists of an upper plate 10 and a lower plate 11 spaced therefrom to provide a space 12 therebetween. The plate 10 has depending flanges 13 extending downwardly along the edges thereof, while the plate 11 has similar flanges 14 extending upwardly therefrom. The flanges 14 are received within the flanges 13 and engage the plate 10 to hold the plate 11 properly spaced from the plate 10. When the plates are assembled, indentations 15 may be formed in the flanges 13 and 14 which secure the parts together.

The plate 10 has a row of holes 16 formed therein which are somewhat larger than the necks of the bottles with which the holder is to be used. The plate 11 has companion holes 17 disposed opposite the holes 16. The holes 16 and 17 register with one another so as to provide openings through the frame and through which the necks of the bottles may be inserted. In the holes 16 and 17 are applied nipples 18 con-

structed of rubber or some other similar, suitable elastic material. These nipples have tubular portions 19 which pass through the frame and which have issuing outwardly therefrom, spaced flanges 21 and 22. The flanges 21 overlie the outermost surface of the plate 10 while the flanges 22 underlie the outermost surface of the plate 11. These flanges hold the nipples securely attached to the frame A and yet permit of compressing the tubular portions 19 thereof to grasp the necks of the bottles with which the holder is to be used. The nipples 18 have flared portions 23 which extend below the tubular portions 19 and lie in continuation thereof. These flared portions assist in guiding the necks of the bottles into the nipples.

Within the space 12 in the frame A is disposed a gang clamp 24. This clamp is preferably constructed of a round rod or wire and is serpentine in form being provided with transverse grip members or portions 25, the individual members being specifically designated by the reference characters *a*, *b*, *c*, etc., and with connecting portions 26 and 27 therebetween. These connecting portions are disposed on opposite sides of the clamp and are adapted to engage the flanges 14 of the plate 11 which serve to guide the clamp for movement within the space 12. The grip members 25 are provided one for each nipple 18 and are normally disposed in the position shown in Fig. 2 adjacent the said nipples. When the gang clamp 24 is moved toward the left as shown in Fig. 4, the various grip members 25 engage the tubular portions 19 of the nipples 18 and flatten the same as shown in Fig. 4. This causes the said nipples to grip the necks of the bottles and to hold the same mounted in the holder. At the end of the gang clamp 24 is provided an arm 28 which is adapted to engage a U-shaped leaf spring 29 disposed within the space 12 at the end of the same. This spring normally urges the gang clamp 24 to the position shown in Fig. 3 in which the end grip member 25*a* engages the flange 13 of the plate 10.

The holder is carried about by means of a bail 31 which consists of a handle 32 and two legs 33 and 34 connected therewith. This bail is constructed from sheet metal being channel-shaped in form and the legs 33 and 34 have ears 35 extending outwardly from the lowermost ends of the same. Rivets 36 extending through said ears and the top plate 10 serve to secure the bail 31 to the plate 10. Within the confines of the bail 31 is an L-shaped lever 37 having a substantially horizontal arm 38 and a substantially vertical arm 39. The arm 38 has ears 41 extending outwardly therefrom which straddle the legs 34 and which are pivotally connected to said leg by means of a rivet 42 which extends jointly through said ears and leg. The lowermost end 43 of the arm 38 projects through a hole 44 in the plate 10 and into the space 12 of frame A where the same is adapted to engage the grip member 25*c* of the gang clamp 24. When the arm 38 of lever 37 is raised upwardly the entire gang clamp is moved toward the left as viewed in Fig. 3 and the various grip members 25 urged against the tubular portions 19 of the nipples 18. A U-shaped keeper 45 pivoted to the holder 32 by means of a rivet 46 is adapted to be swung in position to engage the extreme end of the arm 38 of lever 37 to hold the same in its uppermost position as shown in Fig. 1. This holds the bottles mounted in the holder and prevents disengagement of the holder.

therefrom until the lever 37 is lowered to its position shown in Fig. 3.

For the purpose of limiting the entry of the necks of the bottles into the nipples 18, two U-shaped stops 47 are employed. These stops have legs 48 which are secured to the upper plate 10 and connecting portions 49 therebetween adapted to overlie the nipples 18 with which the said stops are associated. The legs 48 are spaced a sufficient distance to straddle the said nipples. The stops 47 are preferably arranged at the two end nipples of the device whereby the two end bottles serve to limit the entry of the necks of all of the bottles in the row into the various nipples.

For the purpose of illustrating the application of the invention, a number of bottles have been indicated in dotted lines at 51 in Figs. 1 and 4. These bottles are constructed with necks 52 which have caps 53 secured to the outer ends of the same. The holder is particularly useful in picking up bottles from a case or inserting the bottles back into a case as the occasion arises. When the bottles in a case are to be picked up, the holder is placed over the case with the arm 38 of lever 37 in the position shown in Fig. 3. The holder is then lowered by means of handle 32 until the necks 52 of the various bottles 51 enter the various nipples 18 and until the outermost bottles engage the stops 47. By now raising the arm 38 of lever 37, arm 39 of said lever is moved toward the left as viewed in Fig. 3 and the gang clamp 24 shifted toward its position as shown in Fig. 4. In such position, the clamp forces part of the tubular portions 19 of each nipple 18 into engagement with the neck 52 of the bottle received within the same and causes the bottle to be retained within said nipple. The entire device may now be lifted and carried about by means of the handle 32, the arm 38 of lever 37 being held in the position shown in Fig. 1. If it is desired to hold the bottles in place without relying on manual pressure on the lever 37, this may be accomplished by shifting the keeper 45 into the position shown in Fig. 1. When the bottles have been deposited where desired, the same may be released by merely dropping the lever 37 and lifting up the entire holder.

The advantages of the invention are manifest. The device is simple in construction and easy to operate. By means of the nipples employed, injury to the bottles is entirely prevented. The bottles are securely held in position regardless of whether or not the bottles may be of standard size or deviate therefrom. The lever used for operating the gang clamp has an operating arm which is so positioned in relation to the handle of the bail that the same may be readily manipulated while the handle of the bail is being grasped by the user. The stops used with the invention insure the proper insertion of the necks of the bottles into the nipples. By constructing the gang clamp of a round rod, the grip members will not injure the nipples.

Changes in the specific form of my invention, as herein described, may be made within the scope of what is claimed without departing from the spirit of my invention.

Having described my invention, what I claim as new and desire to protect by Letters Patent is:

1. A bottle holder comprising a frame constructed with spaced upper and lower plates, said upper plate having a row of holes therein and said lower plate having a row of companion holes opposite the holes of said upper plate to form 75 pairs of registering holes in said plates for the

reception of the necks of bottles, a gang clamp disposed between said plates and constructed from a rod bent to provide transverse grip portions, one for each pair of holes, and longitudinally disposed connecting portions therebetween and means for shifting said clamp in a direction to urge said grip members toward the openings in said plates.

2. A bottle holder comprising a frame constructed with spaced upper and lower plates, said upper plate having a row of holes therein and said lower plate having a row of companion holes opposite the holes of said upper plate to form pairs of registering holes in said plates for the reception of the necks of bottles, a serpentine gang clamp disposed between said plates and having transverse grip portions, one for each pair of holes, adapted to be moved toward said holes and means for shifting said gang clamp along said frame.

3. A bottle holder comprising a frame constructed with spaced upper and lower plates, said upper plate having a row of holes therein and said lower plate having a row of companion holes opposite the holes of said upper plate to form pairs of registering holes in said plates for the reception of the necks of bottles, a gang clamp disposed between said plates and constructed of

a rod bent to form transverse grip portions and connecting portions therebetween alternately disposed on opposite sides of said clamp and means carried by said frame for shifting said clamp along said frame.

4. A bottle holder comprising a frame constructed with a plate having a number of holes therein, a flexible nipple disposed in each pair of holes for receiving the necks of bottles, a gang clamp disposed between said plates and constructed of round wire bent to form grip portions disposed adjacent said nipples, one for each nipple and means for urging said grip portions of said clamp against said nipples to grip the bottle necks received within said nipples.

PETER HAYWA.
